DRAIN PAN

Cecil N. Blackmore, Hartland, Mich., assignor to General
Motors Corporation, Detroit, Mich.

Filed Aug. 7, 1972, Ser. No. 278,487

Term of patent 14 years

Int. Cl. D12—99
U.S. Cl. D12—155

Fig. 3

Fig. 4

Fig. 5

FIG. 1 is a side elevational view of a drain pan showing my new design;

FIG. 2 is a top plan view;

FIG. 3 is a front elevational view;

FIG. 4 is a transverse section taken along line 4-4 of FIG. 1; and

FIG. 5 is an isometric view.

The broken lines shown in FIGS. 1 and 3 are for illustrative purposes only.

I claim:

The ornamental design for a drain pan, substantially as shown and described.
